UNITED STATES PATENT OFFICE.

JONATHAN D. MAXWELL, OF TARRYTOWN, NEW YORK, ASSIGNOR TO MAXWELL BRISCOE MOTOR COMPANY, OF NORTH TARRYTOWN, NEW YORK.

COOLER FOR AUTOMOBILES AND THE LIKE.

No. 892,864.

Specification of Letters Patent.

Patented July 7, 1908.

Original application filed December 31, 1904, Serial No. 239,160. Divided and this application filed September 28, 1905. Serial No. 280,451.

To all whom it may concern:

Be it known that I, JONATHAN D. MAXWELL, of Tarrytown, New York, have invented certain Improvements in Coolers for

5 Automobiles and the Like, of which the following description, in connection with the accompanying drawings, is a specification, like letters on the drawings designating like parts.

10 This invention relates to automobiles and has for its object certain improvements by which I have secured a more perfect circulation of the cooling medium by a novel construction of the radiator and the siphon ducts leading thereto.

The various features of my invention will be illustrated and described fully in the accompanying drawings and specification and pointed out in the claims.

20 In the drawings, Figure 1 illustrates in plan view the chassis of an automobile with the engine and cooler in view, parts being broken away for the sake of clearness; Fig. 2 illustrates the same in side elevation, the 25 supporting frame being omitted for the sake of clearness; Fig. 3 is a detached view of the radiator with parts of the front broken away to illustrate the internal construction of the radiator; Fig. 4 is a view in cross section 30 taken on the central vertical line Fig. 3, and on an enlarged scale. Figs. 5 and 6 being views in side and front elevation respectively of the sleeve member through which the shaft starter traverses the radiator; and 35 Fig. 7 a view in side elevation of the support for the starter.

In the embodiment of my invention selected for description and illustration as a 40 convenient form to enable ready and complete understanding of my improvements, the part designated by the reference numeral 1 is the power shaft of an automobile supported in a suitable frame comprising side members 2 and end members 3 of any convenient and suitable construction, the shaft 45 being actuated by an engine 4, which in the instance illustrated takes the form of a well-known type of explosion engine having cylinders 5 provided with jackets 6 from which 50 lead siphon ducts 7 conveying the heated water to the radiator 8, the construction of which will be described more at length hereinafter, and from which the cooled water

passes through ducts 9 back to the lower portions of the jackets.

55 In accordance with my invention I provide chambers 10, 11 and 12, into the first of which, 10 at the middle of the radiator, lead the hot water siphon ducts 7 to which reference has been made already, while the cold 60 water ducts 9 lead from the bottom chamber 11, and the position of the mouths of these ducts is preferably about as illustrated in Fig. 3, *i. e.* the ducts 7 being removed a short 65 distance from the sides of the radiator, while the mouths of the ducts 9 are about twice as far from the sides of the radiator. I prefer to apply these chambers to a radiator of the "honey-comb" type, and preferably to that 70 particular form of such radiator as I have illustrated, but to which form I do not limit myself, and the invention whereof I do not claim personally. One of the distinctive 75 features of this type of radiator is found in the zig-zag upright channels connected at every third bend with each other as illustrated at the portion of Fig. 3 broken away, this permitting an interchange of circulation 80 in a direction transverse to the vertical axis of the radiator, which I will designate for the sake of convenience a "primary field".

In operation the hot water entering at 7 within the chamber 10 is able first to distribute itself somewhat through the chamber 10 before beginning to rise through the 85 channels 13, and in so rising it follows a spreading course indicated by the arrows, being distributed completely over the upper field of the rear surface of the radiator until it reaches the chamber 12 by which time it is 90 already fairly well cooled, and thereafter it descends through the portions of the channels at the front of the radiator, these being the coolest by reason of the forced suction produced by the fan 55 from front to rear 95 through the radiator, and by the time the water has reentered the mid-chamber 10, and has passed thence through the lower channels, which form what I designate for the sake of convenience a "secondary field" and 100 reaches the bottom chamber 11, it is thoroughly cooled for withdrawal by the siphon ducts 9.

105 It will be observed that as the water is somewhat cooled before reaching the chamber 12, it is much less likely to lose in quan-

tity by boiling, a common fault of radiators in which the water is allowed to reach the top without such predistribution as the chamber 10 insures, but I provide a steam chamber in 5 the cap 14 and a vent pipe 15 extending down from the cap along the side of the radiator as indicated by dotted lines.

The reference numeral 16 designates a strainer for the supply of water which may 10 be introduced upon removal of the cap 14.

In accordance with an important feature 15 of my invention, I provide means whereby the crank shaft starter 17 shown in Figs. 1 and 2 may be inserted through the radiator 20 to engage the shaft 1, thereby to make it unnecessary to place the radiator very high, or the shaft very low, or diminish the size of the radiator to avoid its traversal by the starter. For this purpose I utilize a sleeve 18, best 25 seen in Figs. 5 and 6, having front and rear flanges 19, presenting a periphery having integral bosses or notched projections 20 to receive the adjacent portions of the channel walls 13, which may be soldered or otherwise secured thereto.

To lend a strong support to the crank shaft starter I may pass through the sleeve 18 a bushing 21, inclined slightly to be coaxial with the shaft 1, and provided with a 30 web or foot 22 having screw or bolt holes 23 by which fastening means may be secured to the frame.

Having thus described my invention, what I claim and desire to secure by Letters 35 Patent is:—

1. In an automobile, the combination with an engine having a cylinder with a jacket for cooling medium, of a radiator having upright channels forming a primary field and a secondary field for passage of the cooling medium, and a central chamber in communication 40 with said channels and arranged substantially horizontally and medially across said radiator, to receive the heated fluid from said jacket, said fluid passing from said central chamber to said primary cooling field, whence it returns into said central chamber, and thence passes to said secondary cooling field, substantially as described.

50 2. In an automobile, the combination with an engine having a cylinder with a jacket for cooling medium, of a radiator having upright channels forming an upper field and a lower field for passage of the cooling medium, and a central chamber in communication with said channels and arranged substantially horizontally and medially across said radiator, intermediate said cooling fields, to receive the heated fluid from 55 said jacket and distribute the same to said upper field, by convection, said fluid returning thence into said central chamber, and passing to said lower field; a duct connecting the upper portion of said jacket with said chamber; and a return duct connecting

said lower field with the lower portion of said jacket, substantially as described.

3. A radiator of the class described comprising a series of upright channels, forming an upper field and a lower field, to circulate 70 the cooling medium, and a chamber traversing said channels medially in a substantially horizontal direction intermediate said fields to receive the said medium before cooling and distribute the same to said upper field, 75 and to receive said medium after it has been partially cooled in said upper field and redistribute it to said lower field, substantially as described.

4. A radiator of the class described comprising a series of upright channels forming an upper field and a lower field, and cross connected at intervals to permit cross circulation of the cooling medium, and a chamber traversing said channels medially in a 80 substantially horizontal direction intermediate said fields to receive the said medium before cooling and distribute and redistribute the same to said upper and lower fields in the order cited, substantially as described. 90

5. A radiator of the class described, comprising a series of upright channels, forming an upper cooling field and a lower cooling field, and a plurality of substantially horizontal transverse chambers, one arranged 95 medially with respect to said fields, and co-operating therewith, substantially in the manner and for the purpose set forth.

6. A radiator of the class described, comprising a series of upright cooling channels, 100 forming an upper field and a lower field, a medial transverse chamber to receive the heated medium and distribute the same to said upper field, an upper transverse chamber in which the partly cooled medium is 105 free to pass toward the cooler surface of said radiator, and thence to said central chamber for redistribution to said lower field, and a lower chamber from which the cooled medium is to be withdrawn. 110

7. A radiator of the class described, comprising a series of upright cooling channels, a medial transverse chamber to receive the heated medium and distribute the same to said channels, an upper transverse chamber 115 in which the partly cooled medium is free to pass toward the cooler surface of said radiator, a lower chamber from which the cooled medium is to be withdrawn, a plurality of inlets for said middle chamber at a 120 short distance from the sides respectively, and a plurality of outlets from said lower chamber, at a greater distance respectively from the sides, substantially as described.

8. The combination with a radiator having upright channels for the circulation of cooling medium, of a sleeve member having a transverse aperture to permit the passage of shaft starting means, said member being provided with integral bosses or projections 125 130

connected with the neighboring channel members, substantially as described.

9. A sleeve member for radiators of the class described comprising a casting having 5 a central aperture for shaft starting means, and having integral bosses or projections to receive the neighboring channel members of said radiator, substantially as described.

10. In a radiator for automobiles, the 10 combination of a sleeve built into the central portion of said radiator, and a crank shaft starter support, comprising a bushing lying within said sleeve, and a fastening member secured to the engine frame, substantially as described.

11. The combination with a radiator for automobiles, built up of a number of cellular members extending from front to rear of 15 said radiator and fastened together at their extremities, of a member having end flanges to receive and support the ends of adjacent cellular members, and a sleeve member to pass a crank-shaft starter, substantially as described.

25 12. The combination with a radiator for automobiles, built up of a number of cellular members extending from front to rear of said radiator and fastened together at their extremities, of a member having end flanges 30 to receive and support the ends of adjacent cellular members, and a sleeve member to pass a crank-shaft starter, said sleeve member being inclined relatively to the longitudinal axis of said cellular members, substantially as described.

35 13. The combination with a radiator having upright channels forming a cooling field to circulate cooling medium, of a sleeve member lying in said field and to which the neighboring channel members are connected, said 40 sleeve member having a bore to pass a starter, substantially as described.

14. In a cooler for the purpose set forth, a series of channels arranged to form a primary 45 cooling field and a secondary cooling field, and a central chamber to which the fluid to be cooled is introduced, and connections to permit passage of said fluid by convection from said central chamber to said 50 primary field, thence through said central chamber again to said secondary field, substantially as described.

55 15. A radiator of the class described comprising a series of upright channels for fluid with transverse interstices for radiation, and a central fluid chamber in communication

with said channels respectively, and dividing said channels into upper and lower radiating fields, substantially in the manner and for the purpose set forth.

60 16. A radiator of the class described, comprising a central receiving chamber to which fluid may be introduced; a primary radiating field comprising a series of channels in communication with said receiving chamber, 65 and extending upward therefrom with transverse interstices for the passage of air or the like; and a secondary radiating field comprising a series of similarly arranged channels in communication with, and extending 70 downward from, said receiving chamber; said instrumentalities co-operating substantially in the manner and for the purpose set forth.

75 17. A radiator of the class described, comprising a central receiving chamber to which fluid may be introduced; a primary radiating field comprising a series of channels in communication with said receiving chamber, and extending upward therefrom with transverse 80 interstices for the passage of air or the like; a vent for steam or vapor in communication with said primary field; and a secondary radiating field comprising a series of similarly arranged channels in communication with, 85 and extending downward from, said receiving chamber; said fluid passing by convection from said receiving chamber to said primary field, and back into said receiving chamber, thence to said secondary field, substantially 90 in the manner and for the purpose set forth.

18. A radiator of the class described, comprising a central fluid receiving chamber; a distributing chamber, above, and connected with, said receiving chamber by a series of 95 upright fluid channels, having interstices for radiation, and serving to conduct fluid from said receiving chamber to said distributing chamber and back to said receiving chamber; and a discharge chamber connected with said receiving chamber by a second series of similarly arranged channels, with interstices for 100 radiation, and serving to conduct said fluid from said mid chamber to said discharge chamber, substantially as described.

105 Signed at Tarrytown in the county of Westchester and State of New York this 15th day of September A. D. 1905.
